Bridgeport, Conn., a corporation of Delaware

Application December 22, 1945, Serial No. 636,904

9 Claims. (Cl. 89—135)

1

The present invention relates, in general, to firearms, and, more particularly, to electric firing means for quick firing guns, typical of which is the automatic firearm shown, in part, in the Marc Birkigt patents, No. 2,159,126 and No. 2,159,127, May 23, 1939. It will be understood, however, that the particular gun shown is by way of illustration only and that the invention is not limited thereby, but includes all modifications and applications within the scope of the appended claims.

Of recent development is a cartridge having an electric primer for use in automatic quick firing guns. It is proposed to fire this cartridge by conducting a high voltage charge, such as the discharge of a condenser, to the electric primer. Early experimental work resulted in the development of an electric bolt which, in general, comprises a bolt provided with a contact pin instead of the customary firing pin, the contact pin being insulated from the bolt and charged by engagement with a conductor carried in the bolt. This conductor has a make and break connection with a condenser terminal which is fixedly supported in the side of the receiver and arranged so that as the bolt moves into battery, the contact pin will be charged and fire the cartridge. The gun is grounded to provide the return circuit.

These experimental electric bolts proved impractical due to a breakdown of the insulation long before the gun had served its normal life and to a tendency of the contact pin to strike the electric primer with substantially the same energy and rigidity as the firing pin in percussion guns with the result that electric primers frequently failed to fire.

An object of the present invention is the provision of improved electric firing means for firing cartridges having electric primers. A further object is to provide a breech bolt with improved electric firing means which will stand up throughout the normal life of the firearm and which will be dependable.

These and other objects, features and advantages of the invention will be more particularly described in the following specification, having reference to the drawing, in which:

Fig. 1 is a fragmentary side elevation, partly in section, of an automatic firearm embodying the electric bolt of this invention.

Fig. 2 is a fragmentary plan view, partly in section, on line 2—2 of Fig. 1.

Fig. 3 is a vertical section on line 3—3 of Fig. 1.

Fig. 4 is a diagram of an induction firing cir-

2

cuit for use with the electric bolt shown in Figs. 1 and 2.

Fig. 5 is a diagram of a capacitative firing circuit adapted for use with the electric bolt shown in Fig. 1 and 2.

Fig. 6 is an enlarged section view of one-half of the electric firing means shown in Fig. 2.

Fig. 7 is a fragmentary side elevation of the front end of one of the slides showing the firing means retaining lug.

Fig. 8 is an isometric view of the forward portion of the right hand slide. The view is from a point to the rear of the front end and from the inside or to the left of the slide as properly oriented in an assembled gun.

The firearm chosen to illustrate the present invention is shown, in part, in Figs. 1, 2 and 3, and comprises a substantially rectangular receiver 10 provided with an upper cartridge feeding aperture 11 and a lower cartridge ejection aperture 12. A barrel 13 is secured in the forward end of the receiver. Mounted in the receiver for reciprocable sliding movement is the breech mechanism which comprises a breech bolt 14 having a longitudinal aperture 14' and a pair of slides 15 and 16, the latter being supported on opposite sides of the bolt and slidably longitudinally relative thereto. Supported within the bolt is an electric firing means indicated generally at 17 which is cooperatively associated with the pair of slides 15 and 16 so as to be displaced within the bolt by relative movement of the slides and bolt in the manner and for the purpose hereinafter described.

35 The bolt 14 is substantially identical to the bolt shown and described in the above-identified Birkigt patents, the recoil movement of which may be initiated by suitable gas operated means comprising a movable element 18 having a member 19 rigidly secured thereto arranged to engage and actuate the slides 15 and 16. The bolt is adapted to be urged forwardly into breech closing position, hereinafter termed its firing position, by an action spring 20 working against

40 a suitable thrust collar in the bolt as hereinafter described. Slides 15 and 16 are arranged to move relative to the bolt for locking and unlocking the latter in and from firing position in the receiver. To this end the bolt is provided with a 45 pivotally mounted pawl 21 oscillatable between upper and lower positions and arranged normally, that is to say, when in its upper position, to lock together the bolt 14 and slides 15 and 16 so as to prevent relative movement thereof, which is

50 55 the relationship of the bolt, slides and pawl 21

whenever the bolt is rearward of its firing position. When, however, the bolt is in firing position and the pawl 21 is moved into its lower position, it locks the bolt 14 in firing position and unlocks the slides 15 and 16 which are then free to move forwardly relative to the locked bolt. This supplemental movement is affected by the provision of springs 22 and 22' mounted in housings 23 and 23' respectively in each slide, each spring bearing at one end against a suitable lug 24 projecting from the adjacent side of the bolt.

The forward movement of the slides 15 and 16 relative to the bolt is adapted to move the electric firing means 17 into engagement with the electric primer *p* of a cartridge *C* in the breech of the barrel. On firing a cartridge, the force of the gases actuate the member 19 which in turn moves the slides together with the electric firing means 17 rearwardly with respect to the locked bolt, thereby elevating the pawl 21 and unlocking the bolt from the receiver and enabling the rearward recoil of the bolt and slides.

The present invention is concerned with the construction and means for operating the improved electric firing means 17 which, as shown, is slidably mounted in the aperture 14' of the bolt. Referring to Figs. 2 and 6, the electric firing means takes the place of a conventional percussion firing pin and comprises a hollow cylindrical body member 25 provided at its forward end with an enlarged substantially conical head 26, the base of which comprises an annulus 27 of greater diameter than the diameter of the body member so as to form a substantially square-shoulder 27' therewith. The diameter of the shoulder 27' is, however, less than the inside diameter of the aperture 14' of the bolt so that the periphery of the annulus will be spaced from the walls of the bolt aperture, see Fig. 2. The rear end of the body member is exteriorly threaded and provided with a cap 28, the outside diameter of the cap also being less than the inside diameter of the bolt aperture so that the periphery of the cap will clear the adjacent walls of the aperture.

A two-part electrical contact element is resiliently mounted in the longitudinal aperture 25' of the body member and comprises a contact pin 29 and a combination spring pilot and anvil 30. The shank of the contact pin is tapered adjacent its forward end and terminates in a sharp conical point 31. The rear end of the pin has an annular shoulder 32, the forward edge of which is adapted to abut an annular shoulder 33 formed in the aperture 25' of the body 25 to limit the forward movement of the pin.

A reduced portion 34 of the pin rearwardly of its annular shoulder 32 provides support for the forward end of a coil compression spring 35, the rear end of which abuts an annular shoulder 36 of the spring pilot and anvil 30. The forward end of the latter is normally spaced a short distance from the rear end of the contact pin 29 and constitutes an anvil to limit the rearward travel of the contact pin. To this end the rear end of the spring pilot 30 seats against the cap 28 so that the force of the compressed spring 35 acts normally to resiliently hold the shoulder 32 of the contact pin 29 against the annular shoulder 33 of the aperture 25' with the conical point 31 of the pin extending forwardly beyond the face of the bolt. Thus, when contact is made with the electric primer of a cartridge, the contact pin 29 is able to yield and move rearwardly against the force of the compressed spring 35,

the anvil 30 acting to limit the rearward movement of the pin. In its rearward position, the conical point 31 of the pin is substantially flush with the face of the bolt. The tapered construction of the contact pin and its sharp conical point 31 are provided in particular so that the aperture 37 in the face of the bolt may be as small as possible in order to preclude blanking the electric primer during firing. In the present embodiment, the aperture 37 is formed in a disk-shaped member 38 which is inlaid in a counterbore 39 formed in the face of the bolt.

The body member 25 and its electric contact pin 29 are supported to travel freely within the aperture 14' of the bolt by front and rear guide bushings 40 and 42 respectively, each of which comprises a cylindrical member having an annular enlargement 43 and 44 respectively at one end of an outside diameter such as to make a smooth running fit within the aperture 14' of the bolt; and an annular flange 45 and 46 respectively at its opposite end, each flange being of less diameter than the aperture 14' so as to clear the walls thereof.

It will be noted that all corners of the bushings are rounded and that the front edge of the enlargement 43 of the forward bushing 40 has a slight taper. The guide bushings are mounted at opposite ends of the cylindrical body member 25 and insulated therefrom by dielectric tubing or sleeves 47. Suitable insulating washers 48, comprising a bone-hard gray vulcanized fiber, are also provided for insulating the faces 43' and 44' of the guide bushings from the adjacent surfaces of the cup 28 and the shoulder 27' of the body member. A second pair of insulating washers 49 are provided on the body member between the opposed faces of the flanges 45 and 46. These insulating washers 49 are separated by a metal contact ring 50 which is carried on the body member 25 and is substantially equal in diameter to the flanges 45 and 46; but which is not insulated from the body member being arranged to make a good electrical contact therewith for the purpose hereinafter described.

The assembly of bushings 43 and 44, insulating sleeves 47, insulating washers 48 and 49 and the contact ring 50 is securely held on the body member 25 by coaction of the shoulder 27' and the screw threaded cap 28, the latter being adapted to be turned up on the threaded end of the body member 25 to force the entire assembly forwardly against the shoulder 27'. A pin 28' may be provided to lock the threaded cap 28 in final position. The contact pin 29, threaded cap 28 and body member 25 are thus insulated from the walls of the bolt but are in electrical contact with the contact ring 50.

The electrical firing means 17 is arranged to be moved back and forth in the bolt aperture by the slides 15 and 16. To this end, each slide is provided at its forward end and adjacent the bottom edge of its inside face 151 and 161 respectively with an integral horizontally disposed laterally projecting lug 52 and 53 respectively (see Figs. 2 and 7) arranged to project through rectangular slots 142 and 143 in adjacent walls of the bolt. Each lug is substantially rectangular in cross section, the edges of the forward and rear ends of each lug being semicylindrical surfaces corresponding in curvature to the rounded ends of the slots 142 and 143 in the bolt. The length of each slot 142 and 143 is, however, greater than the length of a lug so as to enable each lug to have longitudinal movement within its respective

slot. Formed integrally on the longitudinal edge 55 and 56 respectively of each lug are a pair of spaced parallel vertically arranged ribs 57, 57 and 58, 58, respectively, each rib being substantially rectangular in cross section, as shown in Fig. 2, and provided with a downwardly and inwardly sloping bevelled face 57' and 58' respectively. Between each pair of ribs 57, 57 of the lug 52 of the righthand side 15 is an aperture 59 which extends through the lug to the outer face of the slide, the longitudinal axis of the aperture 59 being substantially at right angles to the longitudinal axis of the slide and in a horizontal plane parallel to the horizontal plane of the lug. Fixedly secured within the aperture 59 by a pin is a fiber insulating bushing 60.

Referring to Fig. 2, the slide 15 is provided with a relief groove 61 which extends longitudinally along the outer face 152 of the slide from the front edge thereof rearwardly to a point adjacent the forward wall of its spring retaining housing 23. The groove 61 is substantially rectangular in cross section and is blended at its rear end by a radius into the outer face 152 of the slide. The groove 61 lies in the horizontal plane of the lug 62 and intersects the bushed aperture 59 thereof as shown in Fig. 7.

The lug 53 of the slide 16 on the left-hand side of the bolt is not provided with an aperture, but the outer face of the slide has a groove 62 which extends longitudinally rearwardly from the front edge of the slide. The rear end of the groove is blended by a radius into the outer face 162 of the slide, the overall length of the groove being such as to provide the lead required for induction firing purposes as hereinafter described.

Freely mounted in the bushed aperture 59 of the right-hand lug 52 is an intermediate contact member or conductor 64 which is provided with a rounded head 65 at its inner end and a radius at its outer end. The head 65 is adapted to be held at all times opposite the contact ring 50 of the electric firing means 17 and to this end the lateral spacing of the vertical ribs 57, 57 and 58, 58 of the respective lugs 52 and 53 is such that on assembling the firing means 17 between the lugs of the right and left-hand slides, as shown in Fig. 2, each pair of ribs will make a close fit in the space between the shoulders 43 and 44 respectively of the forward and rearward bushings 40 and 42, thus precluding any longitudinal movement of the firing means relative to the slides and securely holding the contact ring 50 opposite the head 65 of the conductor 64. Thus, longitudinal movement of the slides relative to the bolt, which is permitted by the relationship between the length of the slots 142 and 143 in the bolt and the respective lugs therein, will in turn move the electric firing means 17 relative to the bolt so as to positively advance and retract the contact pin 29 to and from the face of the bolt.

On the wall of the receiver 10 adjacent the breech end thereof is shown a terminal supporting means for the primer firing circuit.

One type of firing circuit is the induction circuit indicated generally in Fig. 4 comprising a suitable source of electrical energy which in the present embodiment is a twenty-four volt battery B for supplying direct current to a primary coil 88. When the circuit through the primary coil is closed, current will build up in the primary coil, during which a relatively high voltage will be induced in the secondary coil 85, the magnitude of the induced voltage being determined by the same factors which determine the ratio of voltage in

the primary and secondary coils of a conventional A. C. transformer. With this circuit, two terminal supporting means are used each comprising a substantially rectangular block 67 consisting of aluminum or other suitable material secured to the receiver wall by fastening means 68. Each block is provided with a central counterbored aperture 69 and is supported on the receiver with its counterbored aperture opposite an aperture 70 in the adjacent wall of the receiver, a suitable flange 71 being formed integrally on the inside face of each block to fit into the corresponding aperture 70 in the wall of the receiver for properly positioning and securing the block thereto. Within each counterbored aperture 69 is a resiliently mounted terminal comprising a cylindrical member 72 having front and rear guide bearings 73 and 74 respectively arranged to slidably engage insulating bushings 75 and 76 which are fitted into the counterbored aperture 69. Projecting from the guide bearing 73 into the relief groove 61 of the adjacent slide 15 is a contact blade 77 having an inclined surface adapted to be engaged by the radius of the conductor 64, as the slides move forwardly in the receiver, to urge the conductor inwardly and engage its head 65 with the contact ring 50 of the electric firing means. The blade 77 is projected into the path of the conductor 64 by the force of a coil spring 79 which is carried on a stem 72' of the terminal, the spring abutting at one end against the guide bearing 74 of the terminal and at its other end against a centrally apertured metal terminal disk 80. The latter is mounted in a counterbored recess 81 formed in the adjacent face of a dielectric cover plate 83 secured to the terminal block. The recess 81 provides clearance for the outer end of the terminal stem 72'. A lead wire 84 for the terminal blade 77 in the right-hand side of the receiver is connected to the secondary coil 85 of a transformer, indicated generally at T in Fig. 4, passes through an aperture 86 in the dielectric cover plate 83 and is secured in engagement with the disk 80 by a solder joint. A lead wire 87 is similarly secured to the terminal blade 77' on the left-hand side of the receiver and is connected to the primary coil 88 of the transformer T. As may be noted by the inspection of Fig. 2, the protrusion of the blade 77' of this terminal is limited by its enlarged flange to an amount less than that permitting it to ride in the bottom of the relief groove 62 of the slide 16. Thus, the lead wire 87 will not be grounded to the slide until, during the final forward movement of the slide, the blade 77' rides up the end of the relief groove and along the face of the slide.

It will be understood that the voltage induced in the secondary coil will be created either by making or breaking the primary circuit. In the present embodiment, the induced voltage in the secondary coil is effected during the building up of current in the primary coil and is accomplished, after closing the firing switch S, by grounding the primary coil 88. This occurs when the terminal blade 77' on the left-hand side of the receiver rides out of the relief groove 62 and engages the adjacent side of the slide 16 as the slides approach their foremost position in the receiver. The lead or length of the relief groove 62 is determined by such factors as the time constant of the primary coil and the time required for the mechanical operation of the gun mechanism. In the present embodiment substantially two milliseconds elapse between the time the bolt 75 is locked in breech closing position and the slides

have carried the contact pin 29 forwardly into contact with an electric primer *p*.

The time constant of the primary coil 88 must, therefore, be greater than two milliseconds and the lead of the relief groove will determine what fraction of the two-milliseconds time interval will be allowed for current build up in the primary coil—this fraction being such as to insure high enough voltage in the secondary coil 85 to fire the electric primer. Immediately prior to the engagement of the contact pin 29 with an electric primer, the secondary terminal 77 on the right-hand side of the receiver contacts the conductor 64 on the slide 15 and discharges the induced charge of the secondary coil 85 to the contact pin 29 and primer *p* which fires the cartridge.

Instead of the induction firing circuit shown, it will be understood that other types of circuits may be used such as the capacitative circuit, shown in Fig. 5, which depends upon the discharge of a condenser *C* charged to a high D. C. voltage by a dynamotor *M*. In this case, the terminal blade 77' and its mounting block 67 is not used, the circuit being a one-wire system grounded to the gun frame.

The operation of the firearm may be summarized as follows:

Following the discharge of a cartridge, the powder gas acting on the movable element 18 and its member 19 moves the latter rearwardly initiating the rearward displacement of the slides 15 and 16 relative to the bolt. This initial rearward movement of the slides carries the electric firing means 17 including the contact pin 29 rearwardly in the bolt. Simultaneously, the conductor 64 is withdrawn from engagement with the blade 77 of the secondary terminal 72 and the terminal blade 77' of the primary coil 88 enters the relief groove 62 in the adjacent wall of the slide 16, thereby breaking the ground connection of the primary coil. Further, the locking pawl 21 is elevated and unlocks the bolt whereupon the bolt and slides are locked together and moved rearwardly in the receiver. The fired cartridge is ejected and a new cartridge fed into the receiver in the usual manner whereupon the bolt is moved forwardly by the action spring 20 into firing position. When the bolt reaches firing position, its forward movement is stopped but the slides 15 and 16 urged by their inertia and the force of the compression springs 22 and 22' continue to move forwardly relatively to the bolt so as to carry the contact pin 29 into engagement with the electric primer *p*. Since the contact pin is resiliently mounted, it will not strike the primer with a force comparable to that of the usual percussion firearm. With the forward movement of the slides 15 and 16 into bolt locking position, the secondary terminal 77 on the right-hand side of the receiver makes contact with the conductor 64 of the right-hand slide 15 and immediately thereafter the left-hand terminal blade 77' rides out of the relief groove 62 in the slide 16 and engages the wall thereof to ground the primary coil 88 of the transformer *T*, whereupon current builds up in the primary coil inducing a high voltage charge in the secondary coil which is carried by the conductor 64 to the contact pin 29 and from thence to the electric primer to fire the cartridge.

Among the more important novel features of the improved electric bolt of this invention are its rugged construction, dependability under extremely adverse firing conditions, long life and interchangeability with the usual percussion bolt of quick acting, automatic firearms of the type

described above. Moreover, the contact pin invariably makes positive contact with the electric primer but will not strike the primer hard enough to destroy it, thus insuring the dependable operation of the firearm.

What is claimed is:

1. In a firearm for firing cartridges having electric primers, a receiver, a barrel secured to said receiver, breech mechanism comprising a bolt 10 slidable in said receiver and slides carried by said bolt, said slides being movable relative thereto; electric firing means supported in said bolt; elements on said slides arranged to cooperatively engage said firing means to move said firing means relative to said bolt into engagement with the electric primer of a cartridge; a source of electrical energy; terminals from said source of electrical energy; means to resiliently support said terminals in said receiver; and a conductor carried by one of said slide elements arranged simultaneously to engage one of said resiliently mounted terminals and said firing means as said slide is moved relative to said bolt to fire said cartridge.
2. In a firearm for firing cartridges having electric primers, a receiver, a barrel secured to said receiver, breech mechanism comprising a bolt 10 slidable in said receiver and slides carried by said bolt, said slides being movable relative thereto; electric firing means supported in said bolt; elements on said slides arranged to cooperatively engage said firing means to move said firing means relative to said bolt into engagement with the electric primer of a cartridge; an electrical induction circuit including primary and secondary coils and a source of voltage; circuit closing means, operated by movement of one of said slides to complete an electric circuit including the source of voltage and said primary coil; and circuit closing means carried by the other slide constructed and arranged to complete a circuit including said firing means and the secondary coil immediately succeeding the closing of the circuit through said primary coil.
3. In a firearm for firing cartridges having electric primers, a receiver, a barrel secured to said receiver, breech mechanism comprising a bolt 10 slidable in said receiver and slides carried by said bolt, said slides being movable relative thereto; electric firing means supported in said bolt; elements on said slides arranged to cooperatively engage said firing means to move said firing means relative to said bolt into engagement with the electric primer of a cartridge; an electrical induction circuit including primary and secondary coils and a source of voltage; a circuit closing contact mounted on said receiver in series electrical circuit with the primary coil and the source of voltage; an actuating surface on one of said slides constructed and arranged to complete said circuit through said contact upon movement of said slide relative to the receiver; and a conductor carried by the other of said slides and arranged to complete an electrical circuit including the firing means and said secondary coil immediately succeeding the closing of the circuit including said primary coil.
4. In a firearm for firing cartridges having electric primers, a receiver, a barrel secured to said receiver, breech mechanism comprising a bolt 10 slidable in said receiver, a slide carried by said bolt and movable relative thereto and a source of electrical energy; electric firing means in said bolt, said firing means comprising a body member, guide bushings mounted on and electrically

insulated from said body member, said bushings having a running fit in said bolt, a primer contact pin mounted in said body member, elements on said guide bushings arranged to cooperatively engage said slide to secure said firing means thereto, said slide being arranged to carry said firing means into contact with the electric primer of a cartridge in said barrel; and a conductor carried by said slide and arranged to connect said contact pin to said source of electrical energy.

5. Electric firing means to adapt a firearm having a reciprocable bolt for firing cartridges having electric primers, said firing means comprising a cylindrical element; guide bushings on said cylindrical element, said bushings having a running fit in said bolt to support said cylindrical element therein; a contact pin in said cylindrical element; dielectric members to insulate said cylindrical member and said contact pin from said guide bushings; a contact ring carried by said body member, said ring being in electrical contact with said pin; and dielectric members to insulate said ring from said bushings.

6. Electric firing means to adapt a firearm having a reciprocable bolt for firing cartridges having electric primers, said firing means comprising a cylindrical element; guide bushings at opposite ends of said cylindrical element, said bushings having a running fit in said bolt to support said cylindrical element therein; a contact pin supported in said cylindrical element for limited movement therein; a spring in said cylindrical element acting to yieldingly partially extend said contact pin therefrom; dielectric sleeves on said cylindrical element to insulate said cylindrical element and said contact pin from said guide bushings; a contact ring carried by said body member between said bushings, said ring being in electrical contact with said yieldable pin; and dielectric washers between the sides of said ring and the adjacent bushings to insulate said ring therefrom.

7. Electric firing means to adapt a firearm having a reciprocable bolt for firing cartridges having electric primers, said firing means comprising a cylindrical element; guide bushings on said cylindrical element, said bushings having a running fit in said bolt to support said cylindrical element therein; a contact pin movably supported in said cylindrical element; a resilient member to yieldingly hold said pin in normal position therein; a stop in said cylindrical member to limit the displacement of said pin from said normal position therein; dielectric members to insulate said cylindrical member and said contact pin from said guide bushings; a contact ring carried by said body member, said ring being in electrical contact with said pin; and dielectric members to insulate said ring from said bushings.

8. In a firearm for firing cartridges having elec-

tric primers, a receiver, a barrel secured to said receiver, breech mechanism comprising a bolt reciprocal longitudinally in said receiver to and from breech closing position and a pair of slides supported on said bolt and movable relative thereto; an electric primer contacting element; means to transmit electrical energy to said primer contacting element comprising a body member mounted in said bolt and arranged to support said contacting element; symmetrical means to support said member in said bolt and to insulate said member from said bolt; a projection integral with each slide arranged to cooperatively engage said symmetrical supporting means at opposite sides thereof; a contact ring on said body member and an electrical conductor mounted in one of said projections arranged to engage said contact ring as said bolt moves into breech closing position to energize said electric primer contacting element.

9. In a firearm for firing cartridges having electric primers, a receiver, a barrel secured to said receiver, breech mechanism comprising a bolt reciprocal longitudinally in said receiver to and from breech closing position and a pair of slides supported on said bolt and movable relative thereto; an electric primer contacting element; means to transmit electrical energy to said primer contacting element comprising a body member slidably mounted in said bolt and arranged to support said contacting element, said body member being slidably mounted by means of symmetrical bushings surrounding said body and provided with means to insulate said element from said bolt; a projection integral with each slide arranged to cooperatively engage said symmetrical bushings at opposite sides thereof; an electric terminal mounted in said receiver; a contact ring on said body between and insulated from said bushings; and a conductor mounted in one of said projections and arranged simultaneously to engage said terminal and said symmetrical contact ring as said bolt moves into breech closing position to energize said electric primer contacting element.
